UNITED STATES PATENT OFFICE.

WILLIAM KLOCKE, OF NEW YORK, N. Y., ASSIGNOR TO E. W. BLISS COMPANY, OF BROOKLYN, NEW YORK, A CORPORATION OF WEST VIRGINIA.

PRESS.

Application filed March 30, 1921. Serial No. 457,016.

To all whom it may concern:

Be it known that I, WILLIAM KLOCKE, a citizen of the United States of America, residing in Woodhaven, in the borough and county of Queens, city and State of New York, have invented certain new and useful Improvements in Presses, of which the following is a specification.

This invention relates to drawing presses, and aims to provide improvements therein.

The present invention provides a press having a simple, strong, efficient driving mechanism, comprising toggles, for a blank holder or die-carrying slide.

The invention further provides a press having a plurality of driving connections for the blank holder or die-carrying slide, comprising rocking parts arranged on axes parallel with the side frames of the press, usually in the direction of the shortest dimension of the press.

The invention further provides a driving connection or connections for a blank holder or die-carrying slide, wherein the driving force is derived from a crank or other eccentric part turning around an axis at right angles to the rocking parts comprising parts of the toggle connections, without involving the use of universal joints, the joints in the connections having simple turning movements around single axes, as, for example, around shafts or pivot pins.

The invention further provides a mechanism, having the characteristics above referred to, wherein the strains imparted by the blank holder or die-carrying slide actuating connections are transmitted to the frame in a direction to be resisted by the ordinary tensile members or reinforcing parts of the press frame. Strains crosswise of the frames are avoided, and the strains of the slide operating mechanism are in the direction of the height of the press, this being in the same direction as the strains arising from the action of the blank holder and punch upon the water.

The invention provides a slide actuating mechanism especially applicable to presses having a wide span between the side frames.

The invention further provides a press wherein sharp angles are avoided in the working parts under stress, and wherein the strains are well balanced and sustained in the press.

The invention further provides a novel combination, and sub-combinations of parts of a press hereinafter more fully set forth.

An embodiment of the invention is illustrated in the accompanying drawing, wherein:

Figure 1 is a view, in front elevation, of a press embodying the invention;

Figure 2 is a view, in side elevation, and partly in section, of the construction shown in Figure 1.

Referring to said drawings, numeral 10 designates a blank holder or die-carrying slide, 11 the bed of the press, adapted to support either a die or blank holder complementary to the part carried by the said slide 10, and 12 designates a punch slide adapted to work either through the bed 11 or slide 10, according to the design of the press, here shown as working through the slide 10.

Numeral 15 designates the frame of the press, which conveniently may comprise the base 16, the side frames or parts 17, reinforced by the tension rods 18 and a yoke or cross-piece 19.

The punch slide is preferably driven by a crank-shaft 20, running longitudinally of the press, and supported in bearings in the side frames 17. In large presses for heavy duty, the crank-shaft 20 preferably extends through the side frames, and has driving parts or gears 21 thereon, at each end, at the outer side of the side frames 17.

The blank holder or die-carrying slide is preferably driven from the same crank-shaft 20, which drives the punch 12, and this is conveniently effected through crank pins 23 projecting from the outer sides of the driving parts or gears 21.

The actuating mechanism 25 for the blank holder or die-carrying slide 10 preferably comprises an actuating slide 30, conveniently mounted upon gibbs, or the like, 31, upon the outer face of the side frames 17, which actuating slide is conveniently connected to the crank pin 23 on the driving part or gear 21, by means of a link 33 connected at one end to said pin 23, and at its other end to a pin 34 on the slide 30, said pins 23 and 30 being parallel, and providing a simple turning or pivotal movement of the link 33 on the said pins.

The actuating mechanism 25 further com-

- prises a toggle 35, connected to the slide 10, as indicated at 36, and to a rocking part 37, bearing on the frame of the press, conveniently in lugs 38 projecting from the frame.
- 5 The toggles 35 are preferably duplicated at the front and rear of the press, as indicated in Figure 2, to provide a symmetrical drive, and, when so constructed, the rocking part 37 conveniently comprises a shaft 39 running crosswise of the frame, usually in the direction of the lesser dimension of the press. Conveniently, the rocking part 37 is fixed to the shaft 39, so that the parts 37 and 39 turn together.
- 10 15 The toggle 35 is preferably actuated by a second toggle 45, the toggle 45 being connected, by means of a pivotal connection 46, at one end, to a crank arm, or the like 47, connected to one leg of the toggle 35, either directly, or indirectly, through the shaft 39, and the other end of said toggle 45 is conveniently connected to a trunnion or pin 48 on the side frame 17, the trunnion 48 and the toggle 45 being duplicated corresponding 20 to the toggles 35.
- 25 The toggle 45 is actuated by the actuating slide 30, being conveniently connected thereto by a link 53, which link is connected to the toggle, conveniently directly thereto by means of the pin 54, which connects the legs of the toggle 45. The link 53 also has a pivotal connection to the slide 30, as indicated at 55.
- 30 The arrangement of the link 53, slide 30, and toggles 45 and 35, is such that, when the toggles 45 and 25 are extended, the link 53 is very nearly at right angles to the toggle 45, and with its pivotal connection 55 moving very nearly parallel to the said toggle 45. The toggles, in their extended position, are in a position where the mechanical advantage thereof, in transmitting the force applied thereto, is greatest, and the link 53 is also in position to apply force in a direct 40 line to the toggle 45. In this position of the toggles 35 and 45, corresponding to the blank-holding position of the blank-holder slide, the parts are in the best positions for transmitting and sustaining 45 the great forces usually involved, and moreover the angles of the connections are sufficiently obtuse that no considerable part of the driving force is resolved into a pull on a bearing or shaft where a turning force is 50 required. Moreover, the pin 23, at this time, is preferably moving in that part of its circle which is generally at right angles to the link 33, and is hence working to its best mechanical advantage on the slide 30.
- 55 60 By reason of the pivot 55 of the link 53 working generally in line with the extended toggle 45, and also by reason of the pin 23 at the same time working generally at right angles to the link 33, there is produced in 65 the blank-holder slide 10, in its blank-hold-

ing position, an effective "dwell" of something more than 90° of the rotation of the crank-shaft 20.

The axes of the shaft 39 and pivots 46, 48, 54 and 55 are parallel, and, hence, the parts 70 all turn in the same or parallel planes. It will thus be seen that none of the joints of the link 33, or of the toggles 35 and 45 and the link 53 have turning movement in more than one plane, all of the joints having 75 a simple turning movement around one axis, and thereby avoiding the use of universal joints, notwithstanding the arrangement of the axis of the drive shaft 20 at right angles to the axes of the toggles 35 and 45 and the 80 link 53.

Moreover, the arrangement of the parts of the blank holder slide actuating mechanism 25 is such that the strains between the ends of the toggles 35 and 45, and between the 85 ends of the link 33, are in the direction of the tension rods 18 of the press, that is, the strains are in the same direction as the strains between the slide 10 and bed 11.

The blank-holder or die-carrying slide 90 mechanism 25 is also preferably duplicated at each side or end of the press, as indicated in Figure 1, that is, the driving connections of the actuating mechanism 25 are preferably symmetrically disposed with relation 95 to the mid-plane 70 of the press, and the mid-plane 71 at right angles to the mid-plane 70.

The inventive ideas herein set forth may receive other embodiments than that herein 100 specifically illustrated and described.

What is claimed is:—

1. A press comprising side frames, a punch driving shaft, a blank-holder or die-carrying slide, and means for operating the same, said means comprising a rock arm adjacent a side frame turning around an axis crossing that of said punch driving shaft, a toggle connected to said arm, an actuating slide, and a link connecting said toggle and actuating slide, said link which is connected to said actuating slide being arranged to extend substantially perpendicular to said toggle when the latter is extended. 110

2. A press comprising side frames, a punch driving shaft, a blank-holder or die-carrying slide, and means for operating the same, said means comprising a rock arm adjacent a side frame turning around an axis crossing that of said punch driving shaft, a toggle connected to said arm, an actuating slide, and a link connecting said toggle and actuating slide, said link which is connected to said actuating slide being arranged to extend substantially perpendicular to said toggle when the latter is extended, said punch driving shaft extending beyond said side frames, and a connection between said punch driving shaft be- 115 120 125 130

yond said side frames and said actuating slide.

3. A press comprising side frames, a punch driving shaft, a blank-holder or die-carrying slide, and means for operating the same, said means comprising a pair of rock-arms adjacent a side frame turning around an axis crossing that of said punch driving shaft, a toggle connected to each of said arms, an actuating slide, and a link connecting each of said toggles and said actuating slide, said links which are connected to said actuating slide being arranged to extend substantially perpendicular to said toggles when the latter are extended.

4. A press comprising side frames, a punch driving shaft extending beyond said side frames, a blank-holder or die-carrying slide, and means for operating said slide, said means comprising an actuating slide on each side frame, driving connections between the projecting ends of said punch driving shaft and each of said actuating slides, a pair of rock-arms at each side of the press, turning around an axis crossing that of said punch driving shaft, a toggle connected to each arm, a link connecting each toggle to the actuating slide on the corresponding side of the press, said links be-

ing connected to said actuating slide and to 30 said arm on axes parallel to said rock-arms, said links which are connected to said actuating slides being arranged to extend substantially perpendicular to said toggles when the latter are extended.

5. A press comprising side frames, a punch driving shaft extending beyond said side frames, a blank-holder or die-carrying slide, and means for operating said slide, said means comprising an actuating slide 40 on each side frame, cranks at the projecting ends of said shaft, and a link connecting each of said cranks and actuating slides, a pair of rock-arms at each side of the press, turning around an axis crossing that of said 45 punch driving shaft, a toggle connected to each arm, a link connecting each toggle to the actuating slide on the corresponding side of the press, said links being connected to said actuating slide and to said arm on 50 axes parallel to said rock-arms, said links which are connected to said actuating slides being arranged to extend substantially perpendicular to said toggles when the latter are extended.

In witness whereof, I have hereunto signed my name.

WILLIAM KLOCKE.
